UNITED STATES PATENT OFFICE.

ARCHIBALD GRIEVE, OF WESTPORT, CONNECTICUT, ASSIGNOR TO CHARLES E. KEMPER, INC., OF WESTPORT, CONNECTICUT, A CORPORATION OF CONNECTICUT.

FUSE.

Application filed May 5, 1921. Serial No. 467,027.

To all whom it may concern:

Be it known that I, ARCHIBALD GRIEVE, a subject of the King of Great Britain, residing at Westport, in the county of Fairfield and State of Connecticut, have invented certain new and useful Improvements in Fuses, of which the following is a specification.

My invention relates to electric fuses, and particularly to a renewable cartridge fuse of the clip type. Specifically, my invention relates to a detailed improvement in the construction shown in my co-pending application Serial No. 442,516, filed February 15, 1921, and is embodied in several forms in the accompanying drawings, in which

Fig. 1 is a broken longitudinal elevation of a cartridge fuse;

Fig. 2 is a side elevation of the washer or button illustrated in Fig. 1;

Fig. 3 is a plan of the button shown in Fig. 2;

Fig. 4 is a partial longitudinal section through a modified construction;

Fig. 5 is an end view of the ferrule shown in Fig. 4; and

Fig. 6 is a longitudinal section through an end ferrule and button illustrating a further modification.

In the construction shown in my prior application above mentioned, the end closure for the fuse casing comprises a bushing secured at the end of the casing, a ferrule screwing on the bushing and a washer within the ferrule, the washer to establish contact with the fuse strip and to deflect the gases and cause them to travel an extended path before escape. In that construction the washer is loosely connected to the end diaphragm of the ferrule. On the escape of the gases, following a rupture of the fuse strip, metal is apt to be deposited in the vent passageways and tends to choke the latter. The permanent association of the washer with the cap renders the cleaning of these passages difficult. To remedy this defect I have now so arranged the gas-deflecting button that it may be removed to permit cleaning of the vent passages.

In the construction shown, the elements are in general the same as those shown in my application above identified, the fuse comprising a casing 10 of fiber or other suitable insulating material provided with

an end bushing 11 permanently riveted in position at 12 and provided with serrations 13 in its neck area which not only assist in maintaining the joint between the casing and the bushing, but also preventing the escape of gases at this point on blowing of the fuse. The bushing is externally threaded at 14 to receive the screw ferrule 15. A shutter 16 such as shown in Keefer Patent No. 1,491,704, April 22, 1924 pivoted on the bushing serves to substantially close the end opening 17 in the latter through which the end 19 of the fuse 18 passes, and is angled over the outer face of the shutter. Resting upon the fuse end and establishing contact therewith is the washer or button 20, provided on its inner face with a contacting boss 21.

In the construction shown in Figs. 1, 2 and 3, the periphery of the button is threaded to engage the threads of the ferrule 15. Marginal slots 22 intersecting the threads afford vent passages through which the gases from the fuse chamber pass. These passages open to a restricted annular chamber afforded between the outer face of the button and the end diaphragm of the ferrule by a shoulder 23 formed in the outer face of the button. The central boss 24 on the outer face of the button projects into or through the central end opening 25 in the ferrule, and the gases are led to the opening 25 by the venting cross slot 26 cut in the outer face of the button. This venting cross slot is preferably arranged at right angles to the slots 22, thus forcing the gases not only to change direction but also to travel an extended path in contact with heat absorbing surfaces before escaping at the opening 25.

It is obvious that when the fuse is blown and the ferrule 15 has been removed to permit a new link 18 to be inserted, the button 20 may be screwed out from the ferrule by means of a screw-driver inserted in the slot 26 and passing through the opening 25. Any metal deposits in the venting passages may then be readily broken or scraped away to leave the latter in proper condition for a succeeding operation of the fuse.

A further feature of advantage in this construction resides in the fact that after the ferrule 15 has been screwed down on the bushing, the contact between the button 20 and the bent-over end 19 of the fuse strip

may be made more perfect by slightly screwing-in the button 20. This has the effect also of locking the cap against accidental unscrewing on the bushing 11 incident to vibration of the fuse support.

In the construction shown in Figs. 4 and 5, the end diaphragm of the ferrule 27 is provided with internal ribs 28 by means of a punch which indents the diaphragm at 10 several points 29. These ribs 28 space the washer 30 slightly from the end diaphragm of the ferrule and thus afford a passage leading to the vent opening 31. The washer 30 rests freely within the cap and is provided with a peripheral thread which sufficiently closely approaches the wall of the ferrule 27 to compel the gases to follow a circuitous path through the thread channels to the venting space 32 between the outer 20 face of the button and the diaphragm of the ferrule. When the ferrule is removed for the renewal of the fuse strip, the washer 30 may be readily forced out by means of a screw-driver inserted through the vent hole 31, and any obstructing deposits may be 25 readily removed.

In Fig. 6 I have shown a still further modification in which the button 33 has its outer boss 34 threaded to engage the tapped 30 end vent hole 35 in the ferrule. Vent channels 36 may be formed either in the boss 34 or in the hole 35 to permit the gases to escape, and the periphery of the washer may be plain, as in my application above identified, or may be provided with a peripheral thread to compel the gases to follow a circuitous path. This construction has an advantage over that shown in Fig. 1 in that there is little or no deposit from the gases 40 on the threads of boss 34 since they escape freely at the passages 36. In the construction shown in Fig. 1, the gases tend to follow the peripheral threads of the button and form a deposit which seals the button 45 in position so that its removal is at times a difficult matter. This modified construction has the advantage, set forth in my application above identified, of maintaining the button as part of the ferrule unit, while 50 nevertheless permitting the washer to be removed to clean the vent passages.

The specific details of construction indicated may be variously modified while retaining the advantages of what I claim as 55 my invention.

I claim—

1. A cartridge fuse having a detachable ferrule with end closure diaphragm aper-

tured on the axis of the ferrule to afford a 60 gas vent, a button detachably held within said ferrule and obstructing direct escape of gas from the fuse chamber to said vent, but affording an extended gas escape passage 65 leading to said vent said button having on its outer face a boss partially obstructing the vent aperture in the end closure diaphragm of the ferrule.

2. A cartridge fuse having a detachable ferrule with end closure diaphragm provided with a central tapped vent hole, in 70 combination with a gas-deflecting button arranged within said ferrule and having on its outer face a boss threaded to screw in said tapped hole and shaped to partially obstruct the latter.

3. A cartridge fuse having a detachable ferrule with end closure diaphragm apertured on the axis of the ferrule to afford a vent, a button arranged within said ferrule and obstructing direct escape of gas from the fuse chamber to the vent in said diaphragm, and a threaded connection between said ferrule and button to permit the latter to be detached from the ferrule said button having on its outer face a boss partially obstructing the vent aperture in the end closure diaphragm of the ferrule.

4. A cartridge fuse having an end closure unit comprising a screw ferrule with vented end closure diaphragm and detachably connected gas-deflecting washer arranged within said ferrule and having a boss which enters and partially obstructs said vent aperture.

5. A cartridge fuse having an end bushing, a ferrule having a screw connection therewith, and a lock washer having a threaded connection with the ferrule.

6. A cartridge fuse having a ferrule with end closure diaphragm, a fuse contacting button within the ferrule and having a screw connection therewith, and an end opening in the ferrule diaphragm to accommodate a button-removing tool.

7. A cartridge fuse having a detachable ferrule with end closure diaphragm provided with a central tapped hole, in combination with a gas-deflecting button arranged within said ferrule and having on its outer face a boss threaded to screw in said tapped hole, said boss having a vent passage opening through its threaded area.

In testimony whereof I have signed my name to this specification.

ARCHIBALD GRIEVE.
